FOUNTAIN BRUSH

Ira Jackson Woodford, Philippi, W. Va.

Application October 23, 1942; Serial No. 463,136

3 Claims. (Cl. 15—124)

The present invention relates to new and useful improvements in fountain brushes designed primarily for use in spreading asphalt on roofs and other surfaces and embodies the provision of a clamping device for clamping a brush transversely across the top of a perforated can in which the asphalt, paint or other material is contained and securing the brush with the bristles thereof projecting laterally from the side of the can so that upon holding the brush in an upright position the asphalt, paint or other material will flow into the bristles of the brush for spreading on the work.

A further object is to provide a device of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which—

Figure 1 is a top plan view.

Figure 2 is a side elevational view.

Figure 3 is a front end elevational view.

Figure 4 is a bottom plan view.

Figure 5 is a top plan view of the paint can holder and brush clamping member with the can and brush removed therefrom.

Figure 6 is a fragmentary sectional view taken substantially on a line 6—6 of Figure 4.

Figure 7 is a fragmentary sectional view through the holder for the bottom of the can.

Referring now to the drawings in detail wherein for the purpose of illustration I have disclosed a preferred embodiment of the invention, the numeral 5 designates a rigid metal supporting ring having its ends 6 secured to the opposite sides of a handle 7.

To the inside of the ring is secured a substantially U-shaped spring clip 8 having its ends free and extending from the outer edge of the ring in a direction parallel to the axis thereof is a rigid supporting member 9 having a spring catch 10 formed at its outer end and adapted for engagement under the bottom of a can 11 when the latter is clamped in the clip 8.

The can 11 is adapted to contain asphalt, paint or other material to be spread on the work and the top of the can is formed with a discharge opening 12 positioned adjacent the outer end of the ring member and at a diametrically opposite

side of the top of the can is formed a vent opening 13.

A brush 14 is placed across the top of the can so that the bristles 15 of the brush will cover the opening 12 as shown to advantage in Figure 1 of the drawings and with the outer ends of the bristles projecting laterally outwardly beyond the sides of the can.

The handle 16 of the brush rests against the surface of the handle 7 and is inserted through a metal loop or strap 17 extending across the handle 7, the handle 16 of the brush being loosely positioned in the strap.

A flexible member 18 of wire or other suitable material has one end inserted through the handle 7 and also through the handle 16 for attachment thereto, the other end of the flexible member 18 extending rearwardly with respect to the handle 7 for attaching to a lateral extension 19 on one side of a lever 20 pivoted as at 21 to the handle 7.

A screw 21' carried by the handle 7 is loosely inserted through the handle 16 of the brush at a point rearwardly with respect to the point of attachment of the member 18. The underside of the handle 16 of the brush in the region of the screw 21' is beveled as shown at 22 to enable rocking of the brush on the screw 21' during movement of the bristles of the brush toward and away from the top of the can 11 to regulate the flow of the contents of the can from the opening 12 into the bristles. The pivotal movement of the lever 20 on its pivot 21 will actuate the flexible member 18 to draw the handle 16 of the brush against the top of the can.

A coil spring 23 has one end attached to the lateral extension 19 and its other end attached to a stationary lug 24 on a plate 25 secured to the handle 7 to exert tension of the flexible member 18 and thus urge the brush in a direction against the top of the can.

A recess 26 is formed in the opposed surfaces of the handle 7 and handle 16 in which a coil spring 27 is positioned to urge the handle 16 outwardly away from the top of the can.

In the operation of the device it will be apparent that when the can 11 is tilted the contents thereof will flow into the bristles 15 of the brush to enable spreading thereof on the work and the discharge of the contents of the can is regulated through the manipulation of the lever 20 to move the brush toward or away from the top of the can in a manner as will be apparent.

It is believed the details of construction, advantages and manner of use of the device will be

readily understood from the foregoing without further detailed explanation.

Having described the invention, what is claimed as new is:

1. A paint spreading device comprising in combination a can clamping member, a handle for the clamping member, a brush including a bristle portion positioned against the top of the can and with the end of the bristles projecting laterally beyond the side of the can and said brush including a handle portion extending parallel with respect to said first-named handle, means pivotally connecting the inner end of the brush handle to the first-named handle and means carried by said first-named handle for adjusting the brush relative to the can.

2. In combination, a device adapted for supporting a container, a brush positioned on one

end of the container and including bristles projecting laterally from the container, a handle for the supporting device, said brush being pivoted to the handle, and means carried by the handle and operatively connected to the brush to adjust the brush relative to the container.

5 3. In combination, a device adapted for supporting a container, a brush including a handle positioned on top of the container and having bristles projecting laterally from the container, a handle for the supporting device, said brush handle being pivoted to the supporting device handle, a lever pivoted to the supporting device handle, a member connecting the lever to the brush to move the brush into position against the container and spring means urging the brush away from the container.

IRAJACKSON WOODFORD.
